US00D995910S

(12) **United States Design Patent** (10) Patent No.: **US D995,910 S**
(45) Date of Patent: ** *Aug. 15, 2023

(54) **HANDLE FOR A SHAVING RAZOR**

(71) Applicant: **The Gillette Company LLC**, Boston, MA (US)

(72) Inventors: **Philipp Goeder**, Frankfurt (DE); **Christopher Ramm**, North Attleboro, MA (US); **Brian Patrick Watson**, Marshfield, MA (US); **Vanessa Christie**, Boston, MA (US)

(73) Assignee: **The Gillette Company LLC**, Boston, MA (US)

(*) Notice: This patent is subject to a terminal disclaimer.

(**) Term: **15 Years**

(21) Appl. No.: **29/768,838**

(22) Filed: **Feb. 1, 2021**

(57) **CLAIM**

The ornamental design for a handle for a shaving razor, as shown and described.

DESCRIPTION

FIG. 1 is a front perspective view of a design of a handle for a shaving razor of the present invention;

FIG. 2 is a front view thereof;

FIG. 3 is a back view thereof;

FIG. 4 is a right side view thereof;

FIG. 5 is a left side view thereof;

FIG. 6 is a top view thereof; and,

FIG. 7 is a bottom view thereof.

The broken lines disclosure of the razor cartridge illustrates the environment of the handle for a shaving razor and forms no part of the claimed design. The remaining broken lines illustrate portions of the handle for a shaving razor and form no part of the claimed design.

1 Claim, 5 Drawing Sheets
